Primary Examiner — Karen S Acker*Assistant Examiner* — Jasmine Mlinarcik(74) *Attorney, Agent, or Firm* — Edmonds & Cmaidalka, P.C.(57) **CLAIM**

The ornamental design for a headwear, as shown and described.

DESCRIPTION

FIG. 1 is a front left perspective view showing the nature and environmental use of a headwear;

FIG. 2 is a front elevation view of the headwear;

FIG. 3 is a rear elevation view thereof;

FIG. 4 is a right side elevation view thereof;

FIG. 5 is a left side elevation view thereof; and,

FIG. 6 is a top plan view thereof.

The partial human figure outlined in broken lines assists in illustrating how the claimed design may appear when worn, but forms no part of the claimed design.

1 Claim, 4 Drawing Sheets(56)
